UNITED STATES PATENT OFFICE.

GRACE MARY QUACKENBUSH, OF NEW YORK, N. Y.

DESIGN FOR A PANEL FOR CHILDREN'S FURNITURE, BEDSTEADS, FENCES, AND SIMILAR TOYS.

47,471.

Specification for Design.

Patented June 15, 1915.

Application filed April 7, 1915. Serial No. 19,812. Term of patent 14 years.

To all whom it may concern:

Be it known that I, GRACE MARY QUACKENBUSH, a citizen of the United States, residing at No. 31 West Sixty-eighth street, in the city of New York, county of New York, and State of New York, have invented a new, original, and ornamental Design for a Panel for Children's Furniture, Bedsteads, Fences, and Similar Toys, of which the following is a specification, reference being had to the accompanying drawing, forming part thereof.

The figure is an elevation of a panel, showing my new design.

I claim:

The ornamental design for a panel for children's furniture, bedsteads, fences and similar toys, as shown.

In testimony whereof I affix my signature in presence of two witnesses.

GRACE MARY QUACKENBUSH.
